United States Patent Office

Des. 185,398
Patented June 2, 1959

185,398

LARYNGOSCOPE

Fred G. Todt, Jr., Manoa, Pa., assignor to George P. Pilling & Son Company, Philadelphia, Pa., a corporation of Pennsylvania

Application December 2, 1957, Serial No. 48,741

Term of patent 14 years

(Cl. D83—12)

FIG. 1.

FIG. 2.

FIG. 3.

Figure 1 is a side elevational view of a laryngoscope showing my new design;

Figure 2 is a right hand elevational view thereof; and Figure 3 is bottom plan view of Figure 1.

The dominant features of my design reside in the full line portions of the drawing.

I claim:

The ornamental design for a laryngoscope, as shown and described.
